Attorney

UNITED STATES PATENT OFFICE

THOMAS B. SLATE, OF GLENDALE, CALIFORNIA, ASSIGNOR TO SLATE AIRCRAFT CORPORATION, A CORPORATION OF NEVADA

ELEVATOR SYSTEM FOR LOADING AND UNLOADING DIRIGIBLE AIRSHIPS

Original application filed April 28, 1926, Serial No. 105,279. Divided and this application filed April 14, 1927, Serial No. 183,872. Renewed December 31, 1929.

This application is a division of my application Serial Number 105,279, filed April 28, 1926.

The object of my invention is to provide a novel elevator system for loading and unloading the ship at stations without bringing the ship down from its flying level and without bringing it near the tops of buildings, trees, or other obstructions that would endanger the ship while the change of passengers and freight is being made, regardless of weather conditions, and to provide a ship capable of operating day and night on schedule time whether the weather is good or bad.

I attain the objects of my invention by the apparatus illustrated in the accompanying drawings, in which—

Figure 1 is a diagrammatic view of the airship in landing position and also in flight;

Fig. 2 is a longitudinal sectional view through the elevator compartment of the airship with the elevators shown in side elevation, a portion of one of the elevators being broken away;

Fig. 3 is a transverse section through the elevator compartment on line 3—3 of Fig. 2; and

Fig. 4 is a top plan view of the elevating mechanism.

Like numerals designate like parts in the respective views.

I provide a novel elevator system including a pair of elevators 22 suspended by chain or cable 23. I provide pulleys 24 mounted in brackets 61 on top of each of the elevators. I provide supports or brackets 26 on which are mounted the motors 31 and 34 as shown in Fig. 3. I provide a shaft 28 on which is mounted a compensating pulley 27 and a large belt pulley 29 which is belted to a reversible motor 31, as shown in Fig. 3.

It is contemplated that suitable depots or stations will be provided in different cities. Messages will be exchanged between stations as to the amount of cargo carried and to be exchanged thus facilitating the transfer of passengers and cargo at stations, and to make possible the efficient use of the capacity of the ship for carrying passengers, express or mail.

At landing stations the airship is not brought to earth but passengers and cargo are delivered and received by means of a novel elevator system. This system includes a pair of elevators connected to the same cable. The length of cable determines the distance from the landing base to the ship and is controlled by a single hoist. After one elevator is lowered to the ground, the elevators are operated by a single motor. 55 One end of the cable is securely affixed at 25 to the shell 1 and is thence threaded through pulleys 24 of one of the elevators 22 and thence over pulley 27 and through pulleys 24 of the other elevator and thence back over the idler pulley 32 to the hoisting drum 33. The guide wires 35 are threaded over idler pulleys 35^a and thence over a pair of drums 33^b. The drums 33^b are of small size so that the guide wires will be lowered at the same 70 speed as the elevator. These guide wires are both hooked onto the first elevator to be lowered and when that elevator reaches the ground at a landing station the hooks carried by the wires are fastened to suitable anchors on the ground a few feet apart to insure the elevators operating a sufficient distance apart to prevent contact when they pass each other at the half-way point. When the guide wires have been hooked to 75 the anchors on the ground a reasonable amount of tension is placed upon the wires by the hoist 33. Any change in position of the ship is compensated for by letting out or taking up a suitable amount of the guide 80 wire between the ship and anchor by the operation of hoist 33. This may be regulated either by the operator on board the airship or automatically by the mechanism illustrated in Figs. 2, 3 and 4 of the drawings. I 85 provide a suitable hook 36 on guide wires 35 as shown in Fig. 2; and suitable eyes or hooks 37 on elevators 22 for anchoring the elevators in their lowered position on the ground, and if desired to serve also as a guide element to limit the swaying of the elevator while being raised or lowered. The guide wires are wrapped on drums on the same shaft with one end of the main elevator cable whereby the proper relation as to 100

length of the wires and cable, respectively, is automatically maintained. As the elevator cable is double, the length of each guide wire is equal to approximately one-half of the length of the elevator cable.

5 This elevator system is automatically flexible to the motion of the ship in all directions without interfering with the elevator service. In other words, as it consists of two elevators, two guide lines, and as the elevators are mounted on the same cable, one is balanced against the other so that they will operate with a minimum of power and to automatically adjust the length of the cable, as 10 illustrated in the drawings, to correspond to variations of the ship's position while the elevators are in operation. When the ship moves up and down changing the distance between the anchoring point and the ship, the 15 guide lines 35 being mounted on drums 33^b which are on the same shaft with the drum 33 over which the main cable 23 travels, will automatically pull out the proper amount of main elevator cable if the ship goes up, since 20 as heretofore pointed out the guide wires carry hooks which are fastened to suitable anchors on the ground when the airship is at a landing place; and as the elevators are both suspended from the same cable and are 25 balanced in the manner shown in the accompanying drawings, the weight of the elevated elevator will automatically take up the portion of the cable connected with the lowered elevator whenever tension on the cable is 30 slackened by movements of the airship, thereby effecting an automatic regulation of the main cable 23 to keep the right amount out, but will not be able to take up more than the 35 guide line will permit.

40 The lowered elevator may, of course, be raised or lowered in the first instance by operating the reversible motor 31, shown in Figs. 3 and 4. The guide wires answer the 45 double purpose of getting the elevator to its proper landing; preventing it from swinging; and automatically adjusting the length of the elevator cable.

What I claim is—

1. An elevator system for an airship of 50 the class described, comprising a pair of balanced elevators operating on the same cable, means for lowering or raising either one of the elevators independently of the other, means for raising and lowering both of the 55 elevators alternately with limited power, guide wires adapted to be anchored to the ground to guide the elevators while being raised and lowered, said guide wires being arranged for automatic adjustment as to 60 length depending on the raising or lowering of the airship relative to the ground where the elevator is anchored, for receiving or discharging passenger or freight.

2. An elevator system for an airship of 65 the class described, comprising a pair of bal-

anced elevators operating on the same cable, means for lowering or raising either one of the elevators independently of the other, means for raising the elevator that is down when the transfer of passengers or freight 70 is completed, means for lowering and raising both of the elevators alternately with limited power, and guide wires adapted to be detachably anchored to the ground whereby said guide wires may be used for guiding 75 one or both of the elevators while they are being raised or lowered.

3. An elevator system for an airship of the class described, comprising a pair of balanced elevators operating on the same cable, 80 means for lowering or raising either one of the elevators independently of the other, means for lowering and raising both of the elevators alternately with limited power, and guide wires detachably secured to each of the elevators, said guide wires having means at their free ends for detachably anchoring the lower end of the wires to the ground, the wires functioning to guide one or both of the elevators while they are being lowered or raised and also functioning to prevent the elevators striking while passing in mid-air, the upper end of the guide wires being wrapped on drums, said drums being mounted on the same shaft with the main elevator cable, the length of each guide wire being approximately one-half the length of the cable from which the elevators are suspended to permit of automatic and simultaneous adjustment of the guide wires and cable as to the distance unreeled from the airship, whereby the ship may vary in elevation without affecting the operation of the elevators as long as tension is kept on the guide wires.
